UNITED STATES PATENT OFFICE.

FRED G. EMMELMANN AND HARRY R. EMMELMANN, OF INDIANAPOLIS, INDIANA.

GASOLENE SOLDERING-IRON.

SPECIFICATION forming part of Letters Patent No. 740,112, dated September 29, 1903.

Application filed April 3, 1903. Serial No. 151,008. (No model.)

To all whom it may concern:

Be it known that we, FRED G. EMMELMANN and HARRY R. EMMELMANN, citizens of the United States, residing at Indianapolis, county of Marion, and State of Indiana, have 5 invented a certain new and useful Improvement in Gasolene Soldering-Irons, of which the following is a specification:

Our invention relates to a new and useful 10 improvement in gasolene soldering-irons, and has for its object to provide a compact, simple, and effective instrument of this character in which the gasolene will be carried in the handle of the iron and gas may be generated, so as to keep the iron at a uniform heat.

With these ends in view this invention consists in the details of construction and combination of elements hereinafter set forth and then specifically designated by the claims.

20 In order that those skilled in the art to which this invention appertains may understand how to make and use the same, the construction and operation will now be described in detail, referring to the accompanying 25 drawings, forming a part of this specification, in which—

Figure 1 represents a side elevation of our improved iron; Fig. 2, a longitudinal section through the forward end of the iron; Fig. 3, 30 a longitudinal section through the rear portion of the iron, the cover not being shown; Fig. 4, an end view of the plug in which the valve-stem is threaded.

A represents a cylinder adapted to contain the gasolene, and brazed upon the forward end of this cylinder is an attachment B, which is reduced at its forward end, so as to form the neck B'. Upon the forward end of this attachment B is formed a flange or 40 shoulder B², and this attachment is externally threaded forward of this shoulder and is also internally threaded, as represented at B³.

C is a plug which is threaded into the forward end of the attachment B, and this plug 45 is internally threaded for the reception of the forward threaded end of the valve-stem D. The plug C is provided with an annular groove E, formed around its periphery near the rearward end thereof. F is a hole or passage extending from the interior of the attachment B and communicates with this annular groove.

Upon the opposite side of the plug is a passage G, which extends from the annular groove at an angle and communicates with the chamber forward of the threaded portion 55 of the valve-stem.

H is a small plug threaded into the forward end of the plug C, and through the center of this plug H is formed a passage very small in diameter and countersunk at its rearward end 60 for the reception of the conical end of the needle-valve D'. Back of the plug C, within the neck of the attachment B, we provide absorbent material I, such as wicking and the like. This prevents the free gasolene from 65 coming in direct contact with the plug C.

J represents the iron-holder, which is in the form of a cylinder bent at right angles at its outer end, as represented at J', and this cylinder is threaded upon the forward 70 end of the attachment B against the shoulder B², and near the rearward end of the cylinder J are provided a series of slots K for the admission of air, and for the purpose of regulating the quantity of air passing through 75 these slots we provide around the exterior of the cylinder a sleeve L, which is provided with slots L', corresponding to the slots in the cylinder, and by turning this cylinder the slots L' may be brought in or out of register 80 with the slots K, and thus regulate the inlet of air.

The soldering-iron M is inserted in the right-angle portion J' of the iron-holder and may be held in place by the set-screw N. To 85 the rearward end of the gasolene-cylinder A is brazed a cap O, which is provided at its rearward end with a stuffing-box and gland P, through which the valve-stem D extends. A knob D² is secured at the outer end of the 90 valve-stem D for the purpose of turning the same.

Q is a nipple extending through the side of the cap O for the purpose of filling the cylinder A with gasolene, and this nipple is ordinarily closed by a screw-cap R. S is a perforated cover surrounding the cylinder, so as to prevent the burning of the operator's hands.

In operation the attachment B is exposed to heat from the exterior for a short time until gas is generated within the cylinder, and then by turning the needle-valve a slight dis-

tance the gas will pass through the passage F, around the annular groove E, through the passage G, through the opening H', and then mixing with the air coming through the slots K will burn with an intense heat through the iron-holder J, and thus heat the iron M, and this flame will sufficiently heat the gasolene contained in the wicking at the rear of the plug C to keep on generating the gas in the well-known manner.

Of course we do not wish to be limited to the exact construction here shown, as slight modifications could be made without departing from the spirit of our invention.

Having thus fully described our invention, what we claim as new and useful is—

1. In a gasolene soldering-iron, a hollow handle adapted to contain the gasolene, a plug threaded in the forward end of said handle, a valve-stem threaded through the plug, said valve-stem extending entirely through the handle and through the stuffing-box at the rear of the handle and provided upon its rear end with a knob, an annular groove provided in the plug around its periphery, a passage extending from the interior of the handle to the rear of the groove, a passage extending from the annular groove to the point forward of the threaded portion of the valve-stem, a burner-plug threaded in the forward end of the other plug provided through its center with a small opening, said opening having a valve-seat for the needle-valve at its rear end, an iron-holder threaded on the forward end of the handle, means for removably securing the iron in the holder, means for admitting air to the interior of the iron-holder, and means for regulating the air-supply, as specified.

2. In a gasolene soldering-iron of the character described, a handle adapted to contain the gasolene, a valve-stem extending longitudinally through the handle and protruding from the rearward end thereof through a suitable stuffing-box, a knob for turning the valve-stem located upon the rear end, a plug secured in the forward end of the handle, the forward end of the valve-stem threaded within this plug, an annular groove formed around the plug near its rearward end, a passage extending from the interior of the handle to this annular groove, a passage located upon the opposite side of the plug extending from the annular groove to the chamber formed by the threaded portion of the plug forward of the threaded portion of the valve-stem, a burner-plug threaded in the forward end of the other plug, said burner-plug provided with an opening formed therethrough, a seat formed at the rear of the burner-plug for the

needle-valve, an iron-holder threaded upon the forward end of the handle, said iron-holder being cylindrical in form and bent at right angles at its outer end, a soldering-iron adapted to be secured in the outer right-angle portion, means for securing the iron in place, slots formed through the cylinder of the iron-holder near its rearward end, a sleeve surrounding the iron-holder and provided with slots corresponding to the slots through the iron-holder, said cylinder adapted to revolve around the holder for regulating the supply of air, as specified.

3. A gasolene soldering-iron, a cylinder adapted to contain the gasolene, an attachment secured to the forward end of the cylinder, said attachment being provided with a shoulder or flange near its forward end and being exteriorly threaded forward of the flange or shoulder, said attachment being inferiorly threaded, a plug threaded into the forward end of the attachment, a needle-valve stem threaded through the plug, said plug being provided with an annular groove formed around its periphery near its rearward end, a passage extending from the interior of the attachment to the annular groove, a passage extending from the annular groove to a point forward of the threaded portion of the valve-stem, absorbent material located in the attachment at the rear of the plug, a burner-plug threaded in the forward end of the other plug, said burner-plug being provided with an opening formed therethrough, small in diameter, a valve-seat at the rear of the burner-plug, an iron-holder threaded over the forward end of the attachment, a soldering-iron, means for removably securing the soldering-iron in the outer end of the iron-holder, slots formed through the iron-holder near its rearward end, means for opening or closing these slots to regulate the supply of air, a cap secured to the rear of the gasolene-cylinder, a stuffing-box secured to the cap at the rear through which the valve-stem extends, a knob secured upon the rearward end of the valve-stem, an opening formed through the cap, a closure for said opening, and a perforated handle surrounding the cylinder, as specified.

In testimony whereof we have hereunto affixed our signatures in the presence of two subscribing witnesses.

FRED G. EMMELMANN.
